UNITED STATES PATENT OFFICE.

FREDERICK H. GRAY, OF LEAVENWORTH, KANSAS.

ELECTRIC-SWITCH-OPERATING MECHANISM.

SPECIFICATION forming part of Letters Patent No. 784,001, dated February 28, 1905.

Application filed March 12, 1904. Serial No. 197,851.

To all whom it may concern:

Be it known that I, FREDERICK H. GRAY, a citizen of the United States, residing at Leavenworth, in the county of Leavenworth and 5 State of Kansas, have invented certain new and useful Improvements in Electric-Switch-Operating Mechanism, of which the following is a specification.

My invention relates to an improved electric- 10 switch-operating mechanism; and my object is to provide a reliable and simple mechanism for operating switches in the circuits of electric signals for railways.

The invention consists in a longitudinal bar 15 pivotally mounted alongside of one of the rails of a track and arranged slightly higher than the rail, so that the wheels of a car or engine passing in either direction will depress said bar, a horizontal lever operatively connected 20 at one end to the longitudinal bar, a short vertical lever operatively connected at its lower end to the opposite end of the horizontal lever, two independent sets of compound levers held by weights in contact with the opposite sides 25 of the upper end of the vertical lever for the purpose of normally holding the latter in a vertical position and through the instrumentality of the horizontal lever normally retain the longitudinal bar in an elevated position, 30 and connections between the compound levers and the circuit-closer and the circuit-opener of the switch, whereby the circuit-closer and circuit-opener are operated by the movement of said compound levers.

35 In order that the invention may be fully understood, reference will now be made to the accompanying drawings, in which—

Figure 1 is a plan view of a section of track provided with my improved mechanism. Fig. 40 2 is a sectional view of the same, taken on line II II of Fig. 1. Fig. 3 is an enlarged broken detail view of a longitudinal bar and its supporting members, forming part of the invention. Fig. 4 is a transverse section, taken on line IV IV of Fig. 2. Fig. 5 is a vertical section taken on line V V of Fig. 1, showing the intervening mechanism between the longitudinal bar and the electric switch. Fig. 6 is a 45 vertical transverse section of the same, taken 50 on line VI VI of Fig. 1.

In said drawings, 1 designates rails of a track supported in the usual way upon ties 2, one pair, 2^a, of which are considerably longer than the others.

3 designates a plurality of brackets secured 55 upon ties 2 and 2^a and provided with upwardly-extending pivotally-connected links 4, pivotally secured at their upper ends to a longitudinal bar 5, arranged beside one of the rails and extending slightly above the latter, 60 so the tread of the wheels of the car or engine passing over the bar in either direction will depress the same. Longitudinal bar 5 is enlarged at its central portion 6 and provided with a slot 7 for the reception of one end of 65 a horizontal lever 8, fulcrumed upon a pivot 9, projecting upwardly from a block 10, secured to the top of ties 2^a. The opposite end of a lever 8 extends through a slot 11 in a casing 12, secured upon the outer portion of ties 70 2^a, and engages the bifurcated lower end of a short vertical lever 13, fulcrumed upon a pin 14, secured to the casing. Lever 13 is normally held in a vertical position by two oppositely-disposed sets of compound levers comprising bell-crank, 15 16 17, fulcrumed upon 75 pivots 18, secured to the casing. The levers are alternately arranged, as shown in Fig. 5, so that the short depending member of levers 17 will rest upon the long horizontal members 80 of levers 16, the short member of the latter in turn resting upon the long member of levers 15. The depending members of the latter in turn contact with the upper opposite sides 85 of lever 13, and thus normally retain the latter in a vertical position, which in turn normally holds the longitudinal bar 5 in an elevated position through the instrumentality of horizontal lever 8. When the compound levers are at rest, their longitudinal members are 90 supported by stops 19, secured to the casing, the longitudinal members being normally held in contact with the stops by weights 20, secured to the outer ends of levers 17. By arranging the compound levers as shown and 95 described it is evident that when disturbed by the depression of bar 5 they will exert a powerful pressure on the upper end of vertical lever 13 and will immediately return the latter to a vertical position and re-elevate bar 5 to its 100

normal position when the same is relieved of the pressure of the wheels.

21 designates the electric switch, which is supported on a partition 22 in the upper portion of the casing, said switch being provided with a circuit-closer 23 and a circuit-opener 24, similar to those shown in my application filed February 1, 1904, Serial No. 191,481.

25 designates a pair of adjustable rods inserted between the outer ends of levers 15, circuit-closer 23, and circuit-opener 24.

When a train approaches from the direction indicated by arrow *a*, bar 5 will be depressed, by being swung in said direction, and swing lever 8 to the position indicated by dotted lines, Fig. 1, causing it to swing the upper end of lever 13 to the right and elevate the longitudinal members of levers 15 16 17 at the right-hand side of the casing, and thus complete the circuit by elevating the lower member 23^a into contact with the upper member 23^b of the circuit-closer. A train passing in the opposite direction will swing the upper end of lever 13 to the left, causing it to operate the compound levers at that side of the case and elevate member 24^a out of contact with point 24^b of the circuit-opener. Thus by locating the switches in reverse positions at the opposite ends of a block or section of track a train entering said section will operate the circuit-closer and set the signals, which will remain in said position until the circuit is opened by the train operating the circuit-opener of the switch at the opposite end of the track-section. Longitudinal bar 5 is of such length that the rear wheel of a coach will contact with one end thereof before the front wheels leave its opposite end, so said bar will be held in a depressed position until the train has passed thereover.

From the above description it is apparent that I have produced a mechanism for operating electric switches which is simple in construction and operation and thoroughly effective for the purpose intended.

Having thus described my invention, what I claim, and desire to secure by Letters Patent, is—

1. In a mechanism of the character described, a longitudinal bar adapted to be depressed by a car passing in either direction, a horizontal lever operatively connected at one end to the longitudinal bar, a short vertical lever operatively connected to the opposite end of the longitudinal lever, an electric switch, and suitable intervening mechanism operatively connecting the switch with the vertical lever.

2. In a mechanism of the character described, a longitudinal bar adapted to be depressed by a car passing in either direction, a horizontal lever operatively connected at one end to the longitudinal bar, compound levers operatively connected to the opposite end of the horizontal lever, and an electric switch operatively connected to the compound levers.

3. In a mechanism of the character described, a longitudinal bar adapted to be depressed by a car passing in either direction, brackets secured to the ties of a track, links pivotally secured at their opposite ends to the longitudinal bar and the brackets, a horizontal lever operatively connected at one end to the longitudinal bar, an electric switch, and intervening mechanism operatively connecting the switch to the horizontal lever.

4. In a mechanism of the character described, a longitudinal bar arranged to swing endwise in either direction, an electric switch having a circuit-closer and a circuit-opener, a set of levers connected to the circuit-closer, another set of levers connected to the circuit-opener, suitable means connecting the longitudinal bar with the two sets of levers whereby one set of the latter is operated when the bar is swung in one direction and the other set is operated when said bar is swung in the opposite direction, and means for returning the levers to their normal positions after they have been operated by the longitudinal bar.

5. A mechanism of the character described consisting of a centrally-notched longitudinal bar arranged to be swung endwise in either direction, a short bifurcated lever, a lever engaging the notch in the horizontal bar and the bifurcated lever, an electric switch having a circuit-closer and a circuit-opener, a set of levers connected to the circuit-closer and engaging one side of the bifurcated lever, another set of levers connected to the circuit-opener and engaging the opposite side of the bifurcated lever, and means for normally holding each set of levers in engagement with the bifurcated lever.

In testimony whereof I affix my signature in the presence of two witnesses.

FREDERICK H. GRAY.
